(57) **CLAIM**

The ornamental design for a speaker transducer, as shown and described.

DESCRIPTION

FIG. 1 is a perspective view of a speaker transducer portion in accordance with an embodiment of my new design;

FIG. 2 is a top plan view thereof;

FIG. 3 is a front elevational view thereof, the rear elevational view being a mirror image;

FIG. 4 is a side elevational view of one side thereof, the opposite side elevational view being a mirror image

FIG. 5 is a bottom plan view thereof;

FIG. 6 is an enlarged cross-sectional view of a portion thereof, taken along 6—6 in FIG. 2; and,

FIG. 7 is an enlarged cross-sectional view of a portion thereof, taken along 7—7 in FIG. 2.

The broken line showing of the circle in the central area of the transducer is for illustrative purposes only and forms no part of the claimed design.
